UNITED STATES PATENT OFFICE.

CHANDLER R. OTIS, OF SAN FRANCISCO, CALIFORNIA.

VALVE-FACING TOOL.

Application filed September 12, 1921. Serial No. 499,906.

To all whom it may concern:

Be it known that I, CHANDLER R. OTIS, a citizen of the United States, residing at San Francisco, in the county of San Francisco and State of California, have invented new and useful Improvements in Valve-Facing Tools, of which the following is a specification.

The present invention relates to an improved valve dressing or facing tool and resides in the provision of a device of this character which will simultaneously resurface the opposing faces of a valve and its seat. I am aware of prior devices of a similar nature wherein a plurality of facing elements in the nature of small cylindrical files are revolvably supported at a fixed angle between two frames or rings, the latter being held in fixed relation, but in this type of tool the facing elements are not adjustable, cannot readily conform to the surfaces being treated and are limited to use on valves of a given size, a different tool for each size of valve being required. There is also a similar tool in which pin like facing elements or files are universally movable and revolvable upon a ring for supporting the same, but tools of this character are objectionable and inefficient, due to the tendency of the facing members to drag when being rotated between the opposed faces of the valve and its seat. This dragging tendency causes the facing elements to be disposed at such angles to the opposed faces of the valve and its seat, that an uneven, inaccurate and ineffective facing action occurs. It is the primary object of my invention to overcome the difficulties and objections above noted and I accomplish this by providing a simple and inexpensive tool which consists of a plurality of files or facing elements revolvably supported at their inner ends only, upon a ring in such manner that the adjustment of said members is limited to movement in the path of radial planes, or in other words, said files may be moved vertically but are prevented from lateral movement whereby the facing elements will automatically adjust themselves to valves of different sizes and will be maintained in position radial to the faces of the valve and seat engaged thereby.

Another object of the invention is to provide a tool of the character described which includes means for compensating for the

leverage action on the facing elements and subsequent lifting up of the supporting frame or ring, whereby a positive and accurate contact of the facing elements with the opposed faces of the valve and seat is assured and a more accurate resurfacing thus provided for. In the devices of the prior art, the down pressure on the valve effected during the facing operation of the valve, thru the inclined working face of the valve, has a tendency to effect a leverage action on the facing elements which fulcrum upon the upper edge of the valve seat. This leverage has a tendency to lift up the supporting frame or ring and as a result of this action, the facing elements are not engaged throughout with the opposed surfaces of the valve and its seat and an uneven and inaccurate resurfacing is produced. Thus, the means above referred to prevents this inaccuracy in valve facing tools of the character defined.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Fig. 1 represents a fragmentary vertical sectional view of a valve seat showing the valve and device of my invention in side elevation and as it would appear when in use.

Fig. 2 is a top plan view of the tool of this invention.

Fig. 3 is a vertical sectional view of the tool showing the facing elements in dotted lines.

Fig. 4 is a detail sectional view of the ring for revolvably supporting the facing elements so that they are movable only in the path of radial planes.

Fig. 5 is an enlarged fragmentary sectional view showing the device as it would appear in use in full lines and in dotted lines the position that the facing members would assume if the coil spring were not employed.

In the accompanying drawings, 1 designates an annular valve seat, 2 a valve hav-

ing an inclined face 3 adapted to engage the seat, 4 the valve stem and 5 a spider in which the stem 4 is reciprocally mounted.

The tool of this invention comprises an annular member 6 which is adapted to surround and be slidable upon the valve stem so as to dispose rotatable facing elements 7 carried thereby in position to engage between the opposed faces of the valve and its seat. The body 6 comprises a cylindrical member 8 having an annular lateral flange 9 upon its upper end. Mounted upon the upper side of the flange 9 is an annular substantially frustro-conical member 10 having a base flange 11 resting upon the flange 9. Mounted upon the flange 11 is an annular guide turret or ring 12 which is secured in position by screws 13 extended thru the flanges 9 and 11 and into said ring 12. The inner surface of the ring or member 12 is spaced circumferentially from the inclined annular face of the member 10. The members 7 are rotatably mounted in openings 14 extending radially thru the ring 12. Each of the members 7 is in the form of a small cylindrical pin having peripheral facing surfaces such, for example, as provided in a rat-tail file. Each member 7 is formed at its inner end with an enlarged head 15. The head 15 is adapted to engage upon the frustro-conical member 10 and the portions of the member 7 which extend thru the ring 12 are non-abrasive and smooth so as to permit of free rotation of the members in the openings 14. To prevent lateral movement of the members and to limit their movement to the path of radial planes, said ring is formed with a plurality of vertical radial recesses or slots 16, opposite sides of which engage opposite sides of the members 7 so as to prevent lateral movement but permit vertical movement of said members 7.

A helical expansion spring 17 is mounted within the member 8 and engages at its lower end a groove or shoulder 18 to limit downward movement of the spring, the upper end of the spring terminating at a point slightly above the upper side of the ring 12.

Operation.

After removing the valve, the body portion 6 is slipped over the stem so as to surround the same and is moved upwardly so that the spring will engage the under side of the valve. The valve is then dropped into place with relation to its seat and the facing elements or files 7 will assume a position shown in Fig. 1 equally engaging opposed faces of and radial to the valve and seat. The valve is then turned in the customary manner and the resurfacing action is commenced. As the valve is turned the facing members are rotated on their own axes and are carried around with the valve and stem during the rotative movement of

such elements. The supporting of the body 6 upon the stem is effected by engagement of the members 7 between the valve and its seat and any tendency to effect a leverage action thru the said member 7, so as to lift the body member 6, is overcome by the spring 17 which is under compression when the device is in operation. The spring 17 tends to push downwardly on the body 6 so as to oppose this leverage action and such action is thereby compensated so that the facing elements are maintained in equal and proper engagement with the opposed faces of the valve and its seat. Continued rotation of the valve thru a short interval of time will cause an accurate and effective facing of the valve and seat simultaneously. By having facing means capable of movement or adjustment only in the path of radial planes, said members are prevented from assuming irregular inclined positions between the opposed faces of the valve and its seat and are maintained in positions radial to the valve and seat, thereby insuring accuracy of resurfacing. This movement or adjustment of the facing members permits of the use of a facing tool for valves of different sizes, since the said members will automatically accommodate themselves to equal engagement with the opposed faces of the valve and its seat. It will thus be seen that the tool of my invention may be effectively used with valves of various sizes.

I claim:

1. A valve facing tool comprising facing members adapted to be disposed between a valve and its seat and means rotatably supporting said members permitting adjustment thereof in the paths of radial planes and preventing lateral adjustment of said members relative to said means.

2. A valve facing tool comprising a plurality of members having peripheral facing surfaces adapted to engage with the opposed faces of a valve and its seat and a member on which said members are revolvable upon their own axes and are adjustable only in the paths of radial planes.

3. A valve facing tool comprising a plurality of facing members having cylindrical portions formed with peripheral facing surfaces and a member in which said facing members are rotatably joined so as to move relative to said member in a vertical plane only.

4. A valve facing tool comprising a plurality of facing members adapted to simultaneously engage with the opposed faces of a valve and its seat and a member adapted to surround the stem of a valve, having openings therein in which said facing members are revolvable and having radial slots in which said facing members are movable.

5. A valve facing tool comprising a plurality of facing members adapted to simulta-

120

125

130

neously engage and rotate between opposed faces of a valve and its seat, and a member rotatably supporting said members and upon which said members are adjustable in 5 one plane only.

6. A valve facing tool comprising facing members adapted to be disposed between a valve and its seat, means rotatably supporting said members permitting adjustment 10 thereof in the paths of radial planes and preventing lateral adjustment of said members relative to said means and a spring on said means arranged to yieldingly engage the valve.

15 7. A valve facing tool comprising a plurality of facing members adapted to simultaneously engage and rotate between opposed faces of a valve and its seat, a member rotatably supporting said members and 20 upon which said members are adjustable in one plane only and a spring carried by said

supporting member and arranged to engage the valve so as to compress when the tool is in operation.

8. A valve facing tool comprising a member having a plurality of radial openings therein, pin-like projecting members revolvable in said openings and a spring carried by and extending above said member. 25

9. A valve facing tool comprising a member having a plurality of openings therein, and pin-like projecting members revolvable in said openings, said members having radial slots in which said projecting members are revolvable. 30

10. A valve facing tool including a plurality of facing members adapted to engage between a valve and its seat and means adjustably supporting said members and maintaining them in position radial to the valve 40 regardless of the adjustment thereof. 35
